DESIGN FOR A HAIR DRIER OR THE LIKE

Harry S. Preble, Jr., New York, N. Y., assignor to
The A. C. Gilbert Company, New Haven, Conn., a corporation of Maryland

Application March 29, 1944, Serial No. 113,068

Term of patent 14 years

(Cl. D86—10)

To all whom it may concern:

Be it known that I, Harry S. Preble, Jr., a citizen of the United States, residing at New York, in the county of New York and State of New York, have invented a new, original, and ornamental Design for a Hair Drier or the like, of which the following is a specification, reference being had to the accompanying drawing, forming part thereof.

Figures 1, 2, 3 and 4 are, respectively, a perspective view, a top plan view, a front view, and a view in side elevation, of a hair drier or the like showing my new design.

I claim:

The ornamental design for a hair drier or the like, substantially as shown.

HARRY S. PREBLE, JR.
